US0D1085741S

(12) United States Design Patent (10) Patent No.: US D1,085,741 S
(45) Date of Patent: * Jul. 29, 2025

(54) FOLDING CHAIR

(71) Applicant: Saifei Fang, Yongkang (CN)

(72) Inventor: Saifei Fang, Yongkang (CN)

() Term: 15 Years

(21) Appl. No.: 29/999,047

(22) Filed: Apr. 16, 2025

(30) Foreign Application Priority Data

Jan. 7, 2025 (CN) 202530008397.8

(51) LOC (15) Cl. 06-01

(52) U.S. Cl.

USPC D6/353; D6/355

(58) Field of Classification Search

USPC D6/330, 334-336, 344, 347, 349, 355,

D6/367, 368, 708, 716; D25/62, 65, 66

CPC A47C 9/00; A47C 9/10; A47C 1/00; A47C

1/031; A47C 4/00; A47C 4/18

See application file for complete search history.
